HOSE CLAMP

David B. Plank, P.O. Box 506, Kalona, Iowa 52247

Filed Mar. 14, 1969, Ser. No. 16,286

Term of patent 7 years

Int. Cl. D8—03

U.S. Cl. D8—229

FIG. 1 is a perspective view of a hose clamp in closed position showing my new design.

FIG. 2 is an elevational view of the opposite side shown in FIG. 1.

FIG. 3 is a side view thereof,

FIG. 4 is a side view opposite to that shown in FIG. 3,

FIG. 5 is a top view thereof,

FIG. 6 is a bottom view thereof,

FIG. 7 is an elevational view similar to FIG. 2 but showing the hose clamp in open position, and

FIG. 8 is a perspective view of a second embodiment of said hose clamp shown foreshortened for convenience of illustration.

I claim:

The ornamental design for a hose clamp, as shown and described.
